Patented June 22, 1971

220,983

REUSEABLE TWO-STAGE AEROSPACECRAFT

James E. Webb, Administrator of the National Aeronautics and Space Administration, with respect to an invention of Harold S. Becker, Palos Verdes Estates, Selwyn Enzer, Orange, William H. Hand, Redondo Beach, Peter Rosati, Garden Grove, and Norman C. Surtees, San Pedro, Calif.

Filed Feb. 5, 1965, Ser. No. 83,867

Term of patent 14 years

Int. Cl. D12—07

U.S. Cl. D71—1

FIG. 4

FIG. 2

FIG. 3

FIG. 1 is a perspective view of the two-stage aerospacecraft which comprises a first stage carrier vehicle having a launchable-in-flight second stage vehicle nested on the top thereof.

FIG. 2 is a plan view of the two-stage aerospacecraft.

FIG. 3 is a side elevational view of the two-stage aerospacecraft; and

FIG. 4 is a rear elevational view of the two-stage aerospacecraft.

What is claimed is:

The original design for reusable two-stage aerospacecraft, substantially as shown.
